TAPE MEASURE

Eugene J. Witchger, Saginaw, Mich., assignor to
 The Lufkin Rule Company, Saginaw, Mich., a
 corporation of Michigan

Application February 16, 1933, Serial No. 657,009

3. Claims. (Cl. 33—138)

The invention relates to tape measures of the so-called push-pull type wherein the tape is drawn out from the casing by pulling and is restored to the casing by pushing, there being no crank for winding the tape, no spring for either suddenly drawing the tape into the casing or suddenly extending it, and no keeper, such as a ratchet, for holding the tape in its extended position.

It is desirable in push-pull tape measures of the kind referred to that both the withdrawal and the rewinding of the tape from and into the case shall be accomplished with a slight amount of effort, and that the force required shall be uniform at all points of extension of the tape from the casing. That is to say, the "feel", by which the user judges the satisfactory operation of a push-pull tape measure, should be substantially the same throughout the entire range of operation. Moreover, there should be no objectionable amount of over-travel, retraction, or creeping movement of the tape when it is released at any point in its range of operation.

Heretofore tape measures of this type have answered these requirements quite satisfactorily, provided the coil spring, used to balance the spring action of the tape itself, was balanced with respect to the character of the tape. In other words, when the tape and spring are properly proportioned, the extending and winding operations are generally smooth and even, so that each push of the tape into the case or each pull out of it requires the same effort. When so properly balanced, the tape will stay in any position to which it is drawn or pushed and has no appreciable tendency to slip either inwardly or outwardly when released.

Under conditions of quantity production of tape measures it is impracticable to balance the strength of each coil spring with the physical characteristics of its tape so accurately as to attain in every tape measure the desired smoothness of action, because there often is some unavoidable slight variation between different lots of spring material or steel tape. An individual tape measure of a manufactured lot, for example, will have a spring which pulls too strongly, so that when the operator releases the tape after having pulled it out to nearly its full extent the tape will slip back a short distance into the case, or it may do so if the case is afterward jarred. Yet this same tape measure will operate satisfactorily at any less extended point in the working range of the tape.

My present invention overcomes the above-

mentioned commercial difficulty and insures a smooth, positive action throughout the entire range of operation of the tape and eliminates slippage. Furthermore, it makes it possible to use a considerably greater length of tape in a given size casing, while giving the desired smoothness and reliability of tape action.

One object of the invention is to provide in the tape casing a novel drag or brake device that shall operate automatically after the manner of a friction brake to keep the tape from being drawn into the case by the pull of the coil spring when the user has released the tape after either drawing it out or retracting it.

Another object of the invention is to provide novel means for securing the drag or brake element to the casing of the tape measure when the casing is assembled.

A third object is to provide an extremely simple and inexpensive device in the form of a flat, thin, and flexible partially-coiled brake band which is secured at one end to the tape measure case and which will envelop and snugly fit the coil of tape at all times while it increases or decreases in size with the winding or unwinding of the tape. The device need exert only a small resistance to the action of the tape and coil spring, both while the tape is being extended and while it is being pushed back into the casing, in order to perform its balancing function effectively. Its action is to dampen the action of the coil spring and by its braking action to produce the desired uniform "feel" of the tape throughout its entire range of operation.

My improved control device is adapted to be used with either flat tapes or with concavo-convex tapes arranged to be pulled out of the case or pushed back by hand.

For the purpose of describing the inventive subject-matter I am showing in the drawing tape measures having non-planar or concavo-convex tapes. The measures are of the push-pull type shown, first, in a preferred form employing a revolving drum and, secondly, in a modified form having no drum. The purpose of this double showing is to make apparent the adaptability of my improved device to tape measures of various known structures, and to demonstrate that my invention is not to be deemed adaptable only to one particular type of tape measure.

With the foregoing and certain other objects in view, which will appear later in the specification, my invention comprises the devices described and claimed and the equivalents thereof.

In the drawing Fig. 1 is a diagrammatic view of a tape measure embodying my improvement, shown with half the case removed, the tape being almost fully wound and the coil spring being almost completely unwound.

Fig. 2 is a similar view of the device shown in Fig. 1, the tape being unwound or extended nearly to its fullest extent, the coil spring being wound.

10 Figs. 3 and 4 are views similar to Figs. 1 and 2 respectively, but with the post and spring omitted to show more clearly the relationship of the novel brake-band to the tape coil and drum.

15 Fig. 5 is an edge view, partly broken away, showing a mode of securing the brake band to the tape case.

Fig. 6 is a perspective view of the resilient band element.

19 Fig. 7 is a fragmentary sectional view of the 20 casing and the brake band, taken on line 7—7 of Fig. 5.

Fig. 8 is a perspective detail of the preferred fastening means, also shown in Fig. 5, by which the brake band is secured to the casing.

25 Fig. 9 is a detail view similar to Fig. 2, but differing therefrom in showing a tape measure structure in which there is no drum upon which to wind the tape.

30 Fig. 10 is a plan view showing the manner of connecting the tape to the coil spring in the structure of Fig. 9.

In Figs. 1 to 5 inclusive I have shown my improved brake device as applied to a tape measure having the usual casing, comprising two pieces 1 35 and 2, formed with a tape opening 3. One of the casing members, 2, has a central post 4 to serve as an anchorage for the coil spring 5.

In the form shown in Figs. 1 and 2 the coil 40 spring 5 has its inner end anchored to the post 4 and is coiled around the post, the outer end 5a of the coil spring being riveted or otherwise secured to a floating drum or hoop 6. The end 7a of the tape 7 is secured to the drum 6. Tape 7 and coil spring 5 are wound in the same sense, 45 so that when the tape is pulled out the coil spring is tensioned.

In Figs. 9 and 10 I have shown a modified form 50 wherein the drum 6 is omitted. Here one end of the coil spring 5 is secured as before to post 4 and its other end 5a is secured directly to the end 7a of the tape 7.

The drum arrangement above described is 55 shown and claimed in my co-pending application, Serial No. 594,114, filed February 19, 1932, patented June 26, 1934, No. 1,964,280.

In the structure shown in Figs. 1 and 2 the drum 6 is adapted for shifting movements in its own plane independently of the casing, as is fully described in the patent referred to.

60 I will now point out the features whereby a new and improved mode of operation of tape measures is made possible by my improved structure.

In Fig. 6 I have shown the thin resilient 65 brake band 8a which is adapted to envelop and press lightly against the periphery of the coil of tape 7. One end 8 of the brake element is secured to the casing members 1, 2, adjacent the tape opening 3, and the body 8a of the brake 70 band is so shaped that it closely envelops the outermost convolution of the tape 7 and expands or shrinks in size according to the size of the tape coil. It distributes frictional pressure against the face of the outer convolution 75 of the tape throughout the greater part of the

circumference of the coil. When the tape 7 is pushed in, assisted somewhat by the balancing spring 5, the tape coil rotates clockwise, as seen in Figs. 1, 4 and 9. The brake element 8a wraps around the coil of tape and acts in the manner of a band brake. When the tape 7 is pulled out the coil of tape rotates counter-clockwise and the brake band 8a follows up the coil, automatically reducing its frictional resistance. The coil then slides somewhat more freely beneath the band as the coil unwinds.

Thus the brake element acts as a dampener, or corrective for any residual unbalance between the resistance of the tape 7 and the winding effort of the coil spring 5, so that throughout the entire range of extension or retraction of the tape the "feel" will be practically the same. In other words, the braking effect is automatically reduced when the tape is unwound against the pull of the spring 5, and increased when the tape is wound by being manually pushed into the casing in the same sense as the pull of spring 5.

It will be observed that there is no positive ratchet or locking action by the brake element, but only a frictional resistance caused by the 25 face-to-face contact of the resilient band with the tape. This resistance does not interfere with winding or unwinding, but on the contrary controls and balances those manipulations so as to insure even and smooth operation.

30 Various means may be employed for securing the end of the resilient brake band element 8a to the tape case, but a preferred structure for this purpose is shown in Figs. 7 and 8, where the upper casing member 1 is formed with an outwardly and downwardly projecting lug 1a struck from the flange of the casing and the lower casing member 2 is provided with a complementary lug 2a which is struck inwardly from the edge of the casing. One end 8 of the brake element 35 is formed with a notch 8b to slip over and engage the lug 2a. When the case is assembled the brake element 8a is secured to it by slipping the notch 8b down over the lug 2a of the lower casing member 2 and then putting the upper casing member 1 in place, so that the lug 1a will form a closure overlying the lug 2a, as shown in Figs. 5 and 7.

In addition to the improved operation of tape 40 measures made possible by the invention, it makes 50 it practicable to house a given tape in a smaller case than before, for the following reasons:

A materially smaller case requires a smaller 55 coil of tape with more turns when wound up. This means more revolutions of the coil spring 5 and greater tension of the spring when the tape is fully extended from the case. This increased tension will undesirably draw the last part of the released tape into the case, in the absence of a braking device. The addition of the new brake 60 element completely eliminates the difficulty described.

Having thus described my invention, what I claim and desire to secure by Letters Patent is:

65 1. In a tape measure of the push-pull type having in combination a casing, a post therein, a coil spring secured to said post, the strength of said spring being insufficient to wind the tape unaided, and a tape secured to the coil spring, a brake element comprising a band of resilient material 70 and having one end fixed to the casing, said band arranged to envelop the greater part of the periphery of the tape coil and to engage and distribute frictional pressure over the peripheral surface of said coil, said band adapted to auto-

matically conform to and closely fit the periphery of said coil as the coil increases or decreases in size during winding and unwinding of the tape, and also adapted to exert appropriate resistance 5 to the action of the winding spring to produce a frictional braking effect to impart smooth and uniform action to the said coil spring and said tape.

2. Means for fixing a frictional brake band to 10 the casing of a tape measure, comprising two casing members, a notch formed in the band near one end thereof and a lug in the edge of one of the casing members formed to engage said notch, and a second lug formed in the edge of the complementary casing member and overlying the first lug, for the purposes set forth.

3. In a tape measure including a casing, means 15 for keeping a tape of the non-planar push-pull

type in neutral condition with respect to forces that tend to produce undesirable creeping movements thereof, said means comprising a winding spring located within the convolutions of the tape and operatively connected thereto, the winding strength of said spring being insufficient to wind the tape unaided, but sufficient to effect the winding of the inner convolutions of the tape when its outer end is manually pushed in the direction of its length toward said spring, and a brake 10 element mounted in the casing and normally engaging the tape coil, the strength of said brake being only sufficient to appropriately reduce by braking action the residual unbalance of the coil spring and the tape and to produce a uniform "feel" of the tape throughout its entire range of operation.
